UNITED STATES PATENT OFFICE.

GEORGE W. DAVIS, OF SEATTLE, WASHINGTON.

CENTRIFUGAL CASTING MACHINE.

Application filed September 29, 1927. Serial No. 222,752.

The object of my invention is the perfecting of centrifugal casting machines to facilitate the operations thereof for a better character of work than hitherto.

5 More specific objects and advantages of the invention will appear in the following description.

The invention consists in the novel construction, adaptation and combination of parts hereinafter described and claimed.

10 In the accompanying drawings,—

Figure 1 is a view partly in side elevation and partly in longitudinal vertical section of a centrifugal casting machine embodying the present invention. Fig. 2 is a transverse section on line 2—2 of Fig. 1, including the mold and a casting not shown in Fig. 1. Fig. 3 is a view in side elevation showing an end of the rotary cylinder, the 15 detachable head therefor and the complementary clutch members illustrated, in disengaged relation, parts of the cylinder and an end member therefor being broken away. Fig. 4 is a fragmentary longitudinal vertical section of the cylinder, a clamping hoop therefor, a portion of the machine frame, and a top roller shown in elevation. Fig. 5 is a fragmentary detail sectional view on line 5—5 of Fig. 1; and Fig. 6 is a sectional view on line 6—6 of Fig. 1.

20 In said drawings, the reference numeral 10 represents, generally, a tubular member hereinafter designated as the cylinder formed of two complementary semi-circular segments 10¹ and 10². Each of said segments is composed of a frame consisting of longitudinal bar elements 11 and 12 rigid with and extending between arcuate end flange elements 13, 14, and intermediate arcuate flange elements 15; and panels 16 for closing the openings between the respective bar and flange elements. The panels 16 are of a circular arcuate shape in transverse section and are provided along their longitudinal edges with flanges 16¹ through which extend bolts 17 for detachably securing the panels to the respective bar elements of a cylinder segment.

25 The bars 11 of one segment are arranged to seat against the corresponding bars of the other segment at a parting line 18 in a plane extending diametrically through the cylinder. The bars 11 at one side of the cylinder are each provided with an offset portion 18¹ to provide in each a recess, the recesses of both frames registering with each other to

provide a doorway 19 located at or about the midlength of the cylinder. The side bars 11 of both segments extend inwardly, as at 20 (Fig. 2) of the inner periphery of the cylinder to a distance approximating the thickness of the mold 21 and terminates in a thin edge, preferably.

30 The flange elements of the cylinder frame structure have tapering peripheral surfaces 65 as 13¹, 14¹ and 15¹ to be engaged in corresponding tapering recesses of annular cylinder heads 22 and 22¹ for the end flanges and in tapering holes of hoops 23 for the intermediate flange elements of both cylinder segments 10¹ and 10². The tapering interfitting connections of said heads and hoops with the frames of the cylinder segments serve to clamp said segments together as a unit.

35 The heads 22 and 22¹ are detachably secured to the cylinder by any suitable means, that shown being hooks 24 carried by the respective heads latching over the adjacent flanges 13 and 14. To prevent the accidental unlatching of said hooks the same may be secured in engaged relation as by means of locking pins 25 (Fig. 3) engaging in lugs, as 26, provided therefor on the heads. 22² in Fig. 3 represents a dowel pin 85 or the like for engaging the head 22 to the cylinder frame against independent rotary movement.

40 The hoops 23 are detachably held in segment coupling relation by forming the outer periphery of each hoop of a V-shape in transverse section and engaging the same in circumferentially grooved rollers 27 and 28 above and below the cylinder. The lower rollers, two for each hoop, are rotatably 90 mounted in chair elements 29 secured in suitably spaced apart relation transversely of the machine upon a carriage 30 arranged for movement transversely of the machine upon track rails 31.

45 The carriage, the chairs, and rollers assembly constitutes a cradle upon which the cylinder is rotatably supported and is movable transversely of the machine into and out of operative position. The cradle with its load is movable by suitable means and preferably by hydraulic power through the medium of a cylinder 32 (Figs. 1 and 2) connected at 32¹ to a base member 33 of the machine frame and having its connecting rod 34 connected to a lug element 35 of the carriage. The hydraulic cylinder 32 is

supplied by water under pressure through suitable known devices not shown. The upper roller 27 pertaining to each hoop is mounted in a holder 36 connected to the machine frame for limited vertical movement.

As shown, a holder 36 is provided with a stem 37 extending through a hole as 38 (Fig. 4) provided in the girder member 39 of the 10 referred to frame, said stem being prevented from rotating by means of a spline 40 secured to the girder acting in a groove provided therefor in the respective stem.

41 represents a spiral spring interposed 15 between the girder 39 and shoulder 36¹ of a holder for yieldably retaining the associated roller in engaged relation with a hoop. 42 represents a nut engageable on screw threads provided upon the stem for limiting the 20 downward movement of the holder and preventing its withdrawal when the cylinder has been removed from its operative position in the machine.

For the doorway 19 is provided a closure 25 or door 43 which is connected by pivots 44 (Fig. 5) to ends of links 45 whose other ends are connected by pivots such as 46 to lugs 47 of the frame part 18¹ of one of the cylinder segments to enable the door to be 30 swung into or out of position to close the doorway. The door is secured in its closed position as by means of a locking bar 48 pivotally connected intermediate its length to the door and engageable with catches 48¹ 35 provided upon the frame parts 18¹. Secured to the inner side of the door and extending through an aperture provided in the mould 21 is a plug 49 (Fig. 5) of a refractory material which, in effect, constitutes a 40 portion of the mold when brought into the position in which it is shown when the door is closed.

The purpose of the doorway and the side 45 opening in the mold 21 is to provide a port through which molten metal is poured into the mold or delivered thereinto through a removable trough or spout as indicated by dotted lines 50 in Fig. 5.

The cylinder is rotated by any suitable 50 power operated means as, for example, the armature shaft 51 of an electric motor 52. Said shaft is journaled in a bearing 53 provided in an end member 54 of the machine frame. Rigid upon said shaft is a brake 55 drum 55 having a lined brake band 56 which is operated by means of a pedal bar 57 (Fig. 6) having a counter weight 58 tending to maintain the bar in its band disengaging position. This bar 57 is desirably connected by means of a rod 59 with a switch 60 closing arm 60 of the circuit wires 61 for the motor. By thus connecting the brake controlling bar 57 by means of the rod 59 with the switch arm 60, the latter may be 65 employed to move the bar 57 from its full

line position (Fig. 6) into its dotted line position 57¹ to release the brake when the switch arm is swung into its dotted line position 60¹ in completing the motor circuit.

Also when the pedal bar 57 is actuated 70 by the operator to apply the brake, the switch arm 60 is brought into its full line position with a consequent break in the motor circuit. As shown in Fig. 6, the connection between the pedal bar and the rod 75 59 is attained by the provision of a stud 62 on the bar acting in an elongated slot 63 in the rod thereby affording lost motion permitting the switch of the motor circuit to be opened prior to the application of the 80 brake.

In starting the motor it is advantageous to do so gradually as by the provision of a rheostat, indicated by 64 in Fig. 1, and which is employed subsequently to the closing 85 of the switch.

Included in the invention is a means for releasably coupling the cylinder 10 to the driving shaft 51 and also a means to induce the flow of air axially through the cylinder 90 to effect the cooling of the metal cast therein.

In said coupling, the cylinder head 22 serves as a clutch member to cooperate with a second clutch member 65 which is splined to said shaft. 95

As shown in Fig. 3, such clutch members are provided upon their opposing ends with hook shaped teeth 66 and 67 arranged circumferentially, the points of the respective teeth being directed to mutually hold when the clutch member on the driving shaft is rotated clock-wise. The end surfaces 66¹ and 67¹ of the respective teeth, however, are inclined, so that when the rotation of the shaft is being suddenly stopped, as in applying the brake, the inertia of the rotating cylinder will cause the clutch teeth 67 of the head 22 to be disengaged from the teeth 66 of the member 65, whereupon the inclined surfaces 66¹ and 67¹ of the respective teeth 100 will act to push the member 65 axially away from the end 22 of the cylinder thereby permitting the cylinder to be removed upon the 105 cradle.

The clutch member 65 is moved into engageable relation with the cylinder by means of shifting lever 69 acting through the medium of a ring 70 provided in a peripheral groove in a hub 71 of said clutch member. 115

The metal-cooling air above referred to 120 is provided by forming the member 65 of two spaced disk elements 72 and 73, providing the disk 73 with a centrally disposed nipple 74 to extend into the opening 75 in the head 22, and providing fan blades 76 in the 125 space between the disk elements 72 and 73.

The cylinder lining 21, or mold proper, is of suitable refractory material, such as of sand, or fire clay, which is built up within the two segments 10¹, 10² or may be made in 130

forms and subsequently placed in the respective segments.

With the segments thus equipped they are secured together by means of the coupling 5 hoops 23 and ends 22 and 22¹ engaging on inclined surfaces 15¹, 13¹ and 14¹, respectively, of the cylinder frame. The cylinder is then placed upon the carriage so that said coupling hoops engage in the grooves of the 10 rollers 28 and thus supported upon the carriage 30 the latter is shifted into operative position in the machine frame, to be in axial alignment with the driving shaft 51 and in engaged relation with the upper rollers 27. 15 The clutch member 65 is then shifted by means of lever 69 into engageable relation with the cylinder end 22. A charge of molten metal is then deposited through the doorway 19 into the mold 21 flowing therein 20 toward both ends of the cylinder. After the charge is thus deposited and the door closed and fastened, the switch arm 60 is moved into circuit closing position, whereupon the operator by suitably regulating the 25 rheostat 64 (Fig. 1) causes the motor and the cylinder which is coupled thereto to be rotated at progressively increasing speed until the cylinder attains a speed most suitable for disposing the molten metal centrifugally 30 against the inner peripheral surface of the mold 21 and of the plug 49 to produce a pipe or the like as represented by W in Figs. 2 and 5. During such centrifugal casting and continuously until the detachment from the 35 cylinder of the clutch member 65 (which contains the fan) an air current is drawn endwise through the work W to cool the same thereby expediting the solidifying and setting of the metal.

40 After the completion of the casting operation above described, the operator bears down with his foot the pedal bar 57 resulting, first, in the switch arm 60 being brought into its open position with respect 45 to the motor circuit and then the application of the brake with a consequent stopping of the rotation of the shaft 51 and the clutch member 65.

When such clutch member is thus stopped, 50 the momentum of the cylinder continues to rotate the same, whereupon the said clutch member is disengaged and pushed away from the cylinder by the action of the revolving teeth 67 of the cylinder end 22.

55 After the cylinder is thus released, it is withdrawn from the machine frame by means of the carriage 30. The hoops 23 and cylinder ends 22, 22¹ are then removed from the cylinder permitting the segments thereof to be separated for removing the casting.

60 The purpose of having the panels 16 removable from the frame of the cylinder is to give access to the interior of the cylinder when the mold is formed about a pattern of 65 the work.

The construction of the machine now preferred by me and the operation of the same will be understood from the foregoing description.

What I claim, is,—

1. In a centrifugal casting machine, the combination of a rotary cylinder having a metal-charging opening in the peripheral wall thereof, a closure for said opening, supporting means for said cylinder, said supporting means being movable transversely of the machine, and releasable power transmission means for rotating the cylinder, said transmission means being movable axially of the machine into and from engaged relation with the cylinder. 70

2. In a centrifugal casting machine, the combination of a rotary cylinder having openings at both ends and adapted to be charged with molten metal through the peripheral wall thereof, said cylinder comprising two complementary semi-circular segments, supporting means for the rotary cylinder, and coupling hoops for uniting the segments of the cylinder, said coupling hoops being held in operative position by the cylinder supporting means. 85

3. In a centrifugal casting machine, the combination with the machine frame, of a rotary cylinder composed of two semi-circular segments, coupling hoops for releasably uniting said segments, a carriage arranged for movement transversely of the machine frame, grooved rollers provided upon said carriage for supporting the cylinder, and grooved rollers depending from the machine frame above the cylinder, the grooves of said rollers serving as guides for the respective coupling hoops and serving to maintain the latter in engaged relation with the cylinder. 95

4. In a centrifugal casting machine, the combination with the machine frame, of a rotary cylinder composed of two semi-circular segments, coupling hoops for releasably uniting said segments, a carriage arranged for movement transversely of the machine frame, and rollers provided upon said carriage for supporting the cylinder, said rollers serving as guides for the respective coupling hoops and serving to maintain the latter in engaged relation with the cylinder. 110

5. In a centrifugal casting machine, a rotary cylinder consisting of two complementary semi-circular members, each of said members consisting of a frame and panel-elements provided with marginal flanges, said frame comprising longitudinal and semi-circular transverse elements rigid with each other and arranged to provide openings to receive the respective panel elements, fastening means extending through said flanges into engaged relation with the longitudinal elements of the frame for detachably securing the panels thereto, and means for sep- 120 130

arably coupling the complementary members together.

6. In a centrifugal casting machine, a rotary cylinder consisting of two complementary semi-circular members, each of said members consisting of a frame and panel elements, said frame comprising longitudinal and semi-circular transverse elements rigid with each other and arranged to provide 10 openings to receive the respective panel elements, fastening means detachably securing the panels to the frame, and means for separably coupling the complementary members together.
- 15 7. In a centrifugal casting machine, a rotary cylinder adapted to contain a lining which serves as the casting mold, said cylinder and lining being each comprised of two complementary members, the cylinder members 20 contacting with each other at a parting line disposed in a plane with the cylinder axis, the cylinder members being provided with lining-supporting elements extending inwardly of the cylinder for a distance approximating the thickness of said lining, and means surrounding the cylinder for releasably coupling the members thereof together.
- 25 8. In a centrifugal casting machine hav-

ing a rotary cylinder, the combination with 30 a power driven shaft and the cylinder, of clutch members for coupling the shaft to the cylinder for driving the latter, means provided on the cylinder for automatically disengaging the clutch when the rotation 35 of the shaft is being stopped, and manually controlled devices for stopping the rotation of the shaft.

9. In a centrifugal casting machine, the combination with a rotary cylinder having 40 an opening in each end thereof, means provided at one end of the cylinder for driving the latter, and a rotary fan actuated by said means to induce a flow of air axially through the cylinder.

45 10. In a centrifugal casting machine, the combination with a cylinder, and means for rotatably supporting the same, said supporting means being movable transversely of the machine, of a power driven shaft, complementary clutch members mounted upon the cylinder and shaft respectively, said clutch members being adapted for engagement with each other when driving the cylinder in one 50 rotary direction only.

55 Signed at Seattle, Washington, this 16th day of September 1927.

GEORGE W. DAVIS.
